ENGINE STARTING DEVICE

John Good, Garden City, N. Y., assignor to Bendix Aviation Corporation, South Bend, Ind., a corporation of Delaware

Application November 14, 1929, Serial No. 407,031

14 Claims. (Cl. 123—119)

The object of the invention is to simplify the operations incident to the starting of automobile or other internal combustion engines to the end that the firing condition will be achieved and maintained with greater certainty and promptness and with less regard to the ability of the operator than heretofore. In brief, it consists in the provision of means acting automatically, that is to say, without conscious effort by the driver, to insure a greater supply of combustible mixture to the engine, as its condition may require, than is ordinarily permitted by the usual idling adjustment devices.

The invention may be readily applied to existing engines and in a great variety of forms but its principles will be readily understood from the illustrative embodiments thereof diagrammatically shown in the accompanying drawing in which Fig. 1 shows a conventional automobile power plant with one form of the invention applied.

Figure 2 is an enlarged sectional view of the by-pass shown in Figure 1, and Figures 3, 4, 5 and 6 are views in section of modified forms of the invention.

This application is in part a continuation of my copending application Serial No. 125,648 filed July 29, 1926, issued November 8, 1932, as Patent No. 1,886,672, relating to improvements in Automobile controls.

Referring to Fig. 1 the engine 1, carburetor 2, intake 3 and a suitable engine cranking agency, which may be an electric motor 4, are arranged in any usual or suitable manner, the circuit of the starting motor being controlled by a switch 5 located on the floor of the car for foot operation or elsewhere, the switch 5 being of substantially the same construction as the one shown in my U. S. Patent No. 1,792,583, issued February 17, 1931. The mixture flow through the intake is determined by throttle 6 under the operator's control, which may be effected by means of foot pedal 7, connected with crank 13 by throttle rod 8. The carburetor as usual, is provided with a so-called engine idling adjustment, such as set screw 9, which determines the minimum opening of the throttle when the foot pedal or accelerator is released, a spring 14 urging the throttle crank into engagement with the set screw. In this position the throttle establishes its normal restriction to mixture flow through the intake corresponding to the idling condition; it is the minimum throttle opening which will permit the engine to run smoothly under its own power.

In the form of Figs. 1 and 2, a by-pass 15 is

connected with the intake 3 around the throttle 6 and is controlled by a ball 16 or other suitably biased valve. When the engine is dead, the ball rests on a supporting pin 17, so that the by-pass is open. The weight of the ball is sufficient to hold it in this position against the suction in the by-pass during cranking but is such that the ball is sucked up to close the by-pass by the sudden vacuum increase incident to firing of the engine and is held closed by the suction which obtains thereafter throughout normal firing of the engine. To start the engine the operator closes the motor switch 5 whereupon the engine is turned over and derives its fuel by way of the intake past the throttle and also through the by-pass, the increased mixture supply furnished by the latter thus ensuring easy cranking and starting. When the engine fires the ball 16 is sucked up to close the by-pass, thus restoring the normal idling mixture flow and avoiding the excessive racing of the engine which often occurs due to the failure of an unskilled driver to return the manual throttle control to the idling position; and in traffic, where the driver's attention should be diverted as little as possible from the manipulation of the car, it is of particular advantage and often a matter of safety that the engine respond readily to the starter and with a minimum of manual adjustment of the controls. In its preferred form the invention contemplates the supply of sufficient fuel not only to facilitate the actual starting of the engine but to cause it to spin fast enough so that its momentum, after the starter pedal has been released, continues its operation at such a speed that the operator has ample time to move his foot to the accelerator and directly control the throttle as conditions may require. There is thus little danger of stalling the engine and though it misfire or tend to stop, either immediately after starting or at any other time, the resulting suction failure instantly drops the ball and the additional mixture passed to the engine sustains its operation, even without attention from the operator.

In Fig. 3 the invention is accomplished by means of a reed valve 26 which overlies a hole 27 in the throttle valve. When the engine is at rest, and during cranking, the valve occupies the position shown in Fig. 4, namely, sprung or biased away from the hole, this being the equivalent of the open by-pass arrangement of Figs. 1 and 2. In response to self-actuation of the engine, the valve is sucked against the throttle to close hole

27 and so restore the normal idling vacuum and mixture supply.

In the form of Fig. 5 the throttle setting is determined by a plunger 28 having a cam surface 29 terminating in a seat 30. The plunger constitutes a stop for the throttle adjustment screw 31 and when the plunger is lowered, so that the adjustment screw engages the seat 30, the throttle is in its normal idling position. In the position shown the plunger has moved upwards by the effect of spring 34 and, by the cam surface 29 engaging the screw 31, has opened the throttle somewhat. This is the at rest, or cranking, setting of the throttle, providing a mixture supply equivalent to that of the form of Fig. 1 when the by-pass is open. The plunger is connected to a bellows 32 which in turn, through the pipe 33, is connected to the engine intake above the throttle. By this means the suction effect of the engine is transmitted to the bellows to collapse the same and so lower plunger 28, and restore the throttle to its normal idle setting. When the engine stops or staggers the plunger is again moved upwards, by spring 34, the latter also serving to overcome any possibility of the bellows being collapsed and the plunger being operated by the cranking vacuum. By varying the size of the opening 35, which connects the intake with pipe 33, the throttle setting control can be made more, or less, sensitive in its response to engine operation; by decreasing the size of the hole a slight lag is interposed between the initiation of the combustion cycle and the return of the throttle to idling position—the delay being occasioned by the time taken to build up sufficient suction in the bellows to collapse the same against the resistance of spring 34. This may be no more than two or three seconds, depending on the size of the opening 35, but may be used to advantage to ensure sustained running of the engine.

Incident to the operation of the invention, as thus described, it will be observed that the intake suction, as well as the volume of mixture passed to the engine, is automatically varied in accordance with the condition of the engine. During cranking the suction is less than normal, due to the wider throttle opening (Fig. 5) or the open by-pass (Fig. 2) and when the engine starts the suction is automatically and somewhat abruptly increased—by the automatic closure of the throttle or by-pass. This effect is of particular advantage when the engine or vehicle is equipped with a suction-operated device designed to occupy one position when the engine is at rest or during cranking and another position when the engine is running. Due to the fact that the intake suction is sub-normal during cranking there is less tendency for the motor device to act during the starting period, and furthermore, since the devices of the present invention also produce a substantial and more or less abrupt suction increase when the engine fires, there is immediately available ample power to operate the motor device to bring about the required adjustment, whether it be the opening of a starter switch, the opening of a choke or any other mechanism which may be arranged for operation by a piston member 21 or its equivalent.

Fig. 6 illustrates a modification of the by-pass device of Fig. 2 and in which the by-pass 40, provided with a check valve or ball 46 as in Fig. 2 is connected at one end on the engine side of the throttle and at the other to a point near the air entrance to the carburetor, preferably just inside

the usual choke valve 41. This is for use with down-draft or other carburetors which by design or otherwise "start rich," that is to say, contain or discharge an excess of fuel on starting, and in this case the flow through the by-pass may be air only, or perhaps air with a small proportion of fuel in it, the effect being to increase the volume of combustible mixture by diluting the otherwise over-rich starting supply. Improved starting is thus obtained and the engine operation sustained as in the forms of Figures 2, 3 and 5.

Having now described my invention, I claim:

1. In an automobile, the combination of an engine, a suction intake supplying fuel thereto, a throttle in the intake, a manual, spring-returned control for the throttle, a stop for limiting the closure of the throttle to pass a minimum idling fuel supply to the engine when said control is not applied, a suction motor device having a connection to the intake and actively responding to pre-determined vacuum change therein and a throttle actuating member operated by said motor device.
2. The combination with the intake manifold of an internal combustion engine and its throttle valve having a normal idling position, resilient means urging the throttle valve only from the idling position to a more open position, means independent of said resilient means for actuating the throttle valve, and means under the control of the manifold suction for counteracting the urge of said resilient means.
3. The combination with the intake manifold of an internal combustion engine and its throttle valve having a normal idling position, an idling restorer for the engine comprising a chamber having communication with the intake manifold whereby a vacuous condition will prevail in the chamber, a movable wall for the chamber movable in response to changes in such vacuous conditions, resilient means normally urging the wall against vacuum responsive movement, and a stem operable by the movable wall under the urge of said resilient means for advancing the idling position of the throttle, said stem being free of said throttle valve to permit independent actuation of the latter.
4. The combination with an internal combustion engine having its intake manifold and a throttle valve therein movable to and from an engine idling position for varying the engine speed, means for manually operating the throttle valve, means independent of said first means for advancing the idling position to accelerate the engine, and means under the control of the suction maintaining in the intake manifold during normal engine operation for normally holding the second means inoperative and adapted to release the latter when the manifold suction falls below a predetermined normal.
5. An idling resorting device for internal combustion engines, comprising, in combination with the intake manifold, the throttle control thereon and the manual means for manipulating the throttle control, of an internal combustion engine, a member detachably engageable with the throttle control when the latter is in its idling position to actuate it throughout a part of its movement, said control being operable independently of said member, means for actuating said member, and means responsive to a normal idling suction influence in the manifold to render said actuating means inoperative.
6. An idling restoring device for internal combustion engines, comprising, in combination with

the intake manifold, the throttle control therefor and the manual means for manipulating the throttle control, of an internal combustion engine, a member detachably engageable with the throttle control when the latter is in its idling position to actuate it throughout a part of its movement, said control being operable independently of said member, resilient means for urging said member to partly open the throttle control, and suction responsive means operable by a normal idling suction influence in the manifold to counteract said resilient means, said responsive means failing in the presence of a predetermined manifold pressure higher than such normal idling suction influence.

7. An idling control for the throttle valve of an internal combustion engine having an intake manifold, comprising a movable stop defining the idling position of the throttle valve, a vacuum motor in communication with the intake manifold, linkage connecting the vacuum motor with said movable stop in such a way that high vacuum tends to move the stop in a direction to permit further closing movement of the throttle, and means in said vacuum motor for yieldingly opposing the action of vacuum thereon, said means yielding at a predetermined high degree of vacuum below which degree the movable stop is held in a fixed advance position to prevent maximum closing movement of the throttle valve.

8. In an automobile, the combination of an engine, a suction intake supplying fuel thereto, a throttle in the intake, a manually operable spring returned control for the throttle, means including a member for determining the position of the throttle when said control is not applied, a suction motor device having a connection to the intake and responsive to vacuum changes therein, and an operative connection between the said member and the motor device.

9. In a carburetor having an induction passage, a throttle therein, throttle stop means for variably limiting the closing movement of the throttle, an element subjected to suction derived from the induction passage posterior to the throttle and movable thereby, and an operative

connection between the throttle stop means and the said element.

10. In a carburetor having an induction passage, a throttle in the passage, means for variably limiting the closing movement of the throttle, and means responsive to the variable vacuum posterior to the throttle for controlling the limiting means whereby the throttle may more nearly close when the vacuum is above a predetermined value.

11. In a carburetor having an induction passage, a throttle therein, a throttle stop for limiting the closing movement of the throttle, and means operative upon increase in the vacuum posterior to the throttle beyond a predetermined value for rendering said stop inoperative whereby the throttle may close to a more nearly closed position.

12. In a charge forming device for an internal combustion engine having an induction passage and a throttle therein: stop means for the throttle comprising a member movable with the throttle, a second member, and an adjustable element mounted on one of the members and cooperating with the other member to limit the closing movement of the throttle, and means responsive to engine suction operatively connected to one of the members.

13. A control device for an internal combustion engine having an induction passage and a throttle valve therein, comprising a movable element adapted to variably limit the closing movement of the throttle, and means responsive to engine vacuum operatively connected to said element.

14. In a carburetor for an internal combustion engine having a throttle controlled induction passage, a movable wall subject to suction derived from the induction passage posterior to the throttle, resilient means resisting movement of the wall, a stop member for variably limiting closing movement of the throttle, and a connection between the stop member and the wall, said connection being so constructed and arranged that the throttle may more nearly close when the suction is high than when it is low.

JOHN GOOD.
